COMBINATION REFRIGERATING - HEATING APPARATUS WITH IMPROVED COIL HEADER STRUCTURE

Don W. Ransdell and Richard T. Ransdell,
Brawley, Calif.

Application May 28, 1948, Serial No. 29,756

4 Claims. (Cl. 62—129)

1

This invention is a coil header structure to be used in connection with evaporating apparatus and by the use of which such apparatus may be used either as a condenser or an evaporator or both alternately.

The primary object of the invention is to provide a header structure by the use of which a standard type evaporating apparatus may be efficiently converted to a condenser so that the apparatus may be used either to heat or cool conditioned air for obvious heating and cooling purposes.

A further and particular object of the invention is to provide a coil header which is of simple and inexpensive construction and which may be quickly and easily attached to evaporating apparatus without materially altering the construction of such apparatus for the purposes herefore set forth.

With the foregoing objects in view, together with others which will appear as the description proceeds, the invention consists in the novel construction, combination and arrangement of parts, all as will be described more fully hereinafter, illustrated in the drawings, and particularly pointed out in the claims.

In the drawings:

Fig. 1 is a vertical sectional view taken through a standard or conventional type of evaporating apparatus and illustrating the coil header of the invention applied thereto with the valve for controlling the flow of fluids through the apparatus, and

Fig. 2 is an enlarged view through one of the headers and showing the detail construction thereof.

Fig. 1 shows in more or less diagrammatical manner, the construction of a standard or familiar type of evaporating apparatus including a casing 5 to enclose the apparatus and divided by suitable partitions so as to include the chambers A, B and C. The lower or bottom chamber C has arranged therein a motor 6 to drive a compressor indicated at 7, and this chamber also includes a condensation receiver indicated at 8. Chambers A and B each contain evaporating apparatus having associated therewith the improved coil header so that the evaporating apparatus may be transformed into a condenser when desired. Each chamber is provided with an air inlet 9 near its lower end and an outlet 10 at its upper end.

The delivery side of the compressor 7 has connected thereto the lower end of a pipe 11 which connects with the central portion of a valve casing 12 arranged within the chamber B, and this valve casing is equipped with valves 13 and 14

2

controlled by operating wheels or handles 15 and 16. The casing 12 has communicating therewith the lower ends of pipes 17 and 18, the flow of fluid through which is controlled by valves 13 and 14.

- 5 The pipes 17—18 extend upwardly in the chambers A and B and are connected at their upper ends to headers 19 and 20. These headers are disposed preferably in horizontal position within their respective chambers and above and substantially parallel with lower headers 21 and 22. A coil pipe 23 connects each of the upper headers with the lower headers, and the headers 21—22 are connected with return pipes 24—25, which lead back through a common return 26 to condensation receiving tank 8 in the compartment C. From the condensation receiver 8 a pipe 27 leads to a conventional type of heat exchanger 28, a strainer 29 being disposed in the line for obvious purposes. Extending from the heat exchanger 28 is an upwardly directed pipe 30 leading to a union 31 and through spaced risers 32 controlled by valves 33. Pipes 34 lead from these risers to the lower headers 21—22 in the chambers A and B respectively.
- 15 Each of the pipes 34 is equipped with a conventional expansion valve 36, and the ends of the pipes 34 constitute nozzles 36' extending into the adjacent ends of the coils 23, as shown more particularly in Fig. 2 of the drawings.
- 20 The valve casing 12 has connected with the lower side thereof return lines 37 which connect with the heat exchanger 28 and then by a pipe 38 to the compressor 7.

- 25 The behavior of the apparatus as described 35 will depend upon the direction of flow of refrigerant gas passing through the tubes 23, the directional flow being controlled by the positions of valves 13—14. In using the apparatus as a condenser, the course of the hot compressed 40 vapor refrigerant will be as shown in chamber A wherein coil 23 is used as a condenser. The hot compressed vapor refrigerant passes from the discharge side of the compressor and through the valve 12 into pipe 17 and into upper header 19, 45 from whence it takes a downward course through the coil 23 and is condensed and accumulated in header 21 and returns by by-pass tube 24, through riser 32 to pipe 26 to the receiver tank. In this process, the heat from the hot compressed refrigerant is transferred to the condenser apparatus, and a forced draft of air caused by fan 40 at the upper end of chamber A draws air through the chamber A and delivers it in a conditioned state through the discharge opening 10 at the 50 upper end of the chamber.

When the coil 23 is adapted to serve as an

evaporator, the refrigerant under pressure will pass through the riser 32 and into pipe 34 as shown in chamber B, from whence it passes through expansion valve 36 and through the nozzles 36' and into the lower ends of the coil members 23 and the coil 23 in chamber A in this instance is used as an evaporator instead of as a condenser as previously described. These nozzles 36' carry the refrigerant beyond the header 21, thus eliminating the possibility of the refrigerant by-passing any of the tubes 23 and causes an even distribution into and through all of the tubes of the bank 23. The refrigerated gas is evaporated in its travel through the tubes 23 causing a chilling effect on the evaporator apparatus, and it then passes into the upper header 26 and on into tube 17, to be returned through the valve 13, through pipe 37, heat exchanger 28 and to the suction side of the compressor through pipe 38. A forced draft of air created by fan 40 in such case in the upper part of chamber A causes air entering through the lower opening 9 to pass over and around the coils 23 being chilled in this course before being discharged through the opening 10, as will be understood.

From the foregoing, it is apparent that by the construction and arrangement of the coils above described and in the association in the manner set forth with a conventional or standard evaporating apparatus, the apparatus may carry out the functions of a condenser or an evaporator, or both alternately by mere manipulation of the valves to bring about the desired or required direction of flow of the liquid through the pipes.

We claim:

1. In apparatus of the character described, a combination evaporator and condenser-unit comprising: an upper and a lower header, a coil connecting said headers, a conduit in communication with said upper header and serving as a feeding line when the unit is operated as a condenser and as a return line when the unit is operated as an evaporator, a return line connected to said lower header for returning liquid when the unit serves as a condenser, a feed line having an expansion valve therein extending through said lower header and into said coil to serve as an inlet to the coil when the coil serves as an evaporator.

2. In a combination refrigerating-heating apparatus of the character described, a coil having

an upper end and a lower end, an upper header in communication with said upper end of said coil, a lower header in communication with said lower end of said coil, separate conduits in communication with corresponding ones of said headers, and a nozzle extending through said lower header and extending into said lower end of said coil.

3. In a combination refrigerating-heating apparatus of the character described, a coil having an upper end and a lower end, an upper header in communication with said upper end of said coil, a lower header in communication with said lower end of said coil, separate conduits connected respectively to said upper and lower headers, a tubular nozzle extending through said lower header and extending centrally within and coaxially of said lower end of said coil.

4. In reversible refrigeration apparatus for heating and cooling, a heat exchanger adapted to function either as a condenser or as an evaporator of the dry expansion type and comprising a plurality of refrigerant passages, extending from an upper level to a lower level, means for supplying vaporized refrigerant to the passages adjacent the upper level when the heat exchanger is operated as a condenser, means adjacent said lower level for discharging vaporized and liquid refrigerant, the last mentioned means including a header in communication with a line serving as a discharge line when the exchanger serves as a condenser, and a conduit extending through said header and into the lowermost end of said refrigerant passages, said last mentioned conduit being of smaller diameter than said refrigerant passages and serving as an inlet when the exchanger serves as an evaporator, whereby the liquid admitted by the several connections to the refrigerant passages is maintained separated.
